US0D1082148S

(12) **United States Design Patent** (10) **Patent No.:** **US D1,082,148 S**
(45) **Date of Patent:** **** Jul. 1, 2025**

(54) **COSMETIC PRODUCT CONTAINER**

(71) Applicant: **EOS PRODUCTS, LLC**, New York, NY (US)

(72) Inventors: **Jonathan Teller**, New York, NY (US); **Sanjiv Mehra**, New York, NY (US); **Peter Waxman**, New York, NY (US); **Joseph Speter**, New York, NY (US); **Sherry Jhawar**, New York, NY (US); **Hamish Campbell**, New York, NY (US)

(73) Assignee: **EOS PRODUCTS, LLC**, New York, NY (US)

(**) Term: **15 Years**

(21) Appl. No.: **29/837,835**

(22) Filed: **May 9, 2022**

(63) Continuation of application No. 29/679,333, filed on Feb. 5, 2019, now Pat. No. Des. 951,548, which is a continuation of application No. 29/573,625, filed on Aug. 8, 2016, now Pat. No. Des. 840,107, which is a continuation-in-part of application No. 29/570,374, filed on Jul. 7, 2016, now Pat. No. Des. 838,912, and a continuation-in-part of application No. 29/488,848, filed on Apr. 23, 2014, now Pat. No. Des. 764,113, and a continuation-in-part of application No. 29/488,846, filed on Apr. 23, 2014, now Pat. No. Des. 771,873, and a continuation-in-part of application No. 29/488,850, filed on Apr. 23, 2014, now Pat. No. Des. 769,533, and a continuation-in-part of application No. 29/488,847, filed on Apr. 23, 2014, now Pat. No. Des. 764,112, and a continuation-in-part of application No. 29/488,849, filed on Apr. 23, 2014, now Pat. No. Des. 764,114, and a continuation-in-part of application No. 29/488,104, filed on Apr. 16, 2014, now Pat. No. Des. 764,111, and a continuation-in-part of application No. 29/488,103, filed on Apr. 15, 2014, now Pat. No. Des. 764,110, and a continuation-in-part of application No.

29/488,102, filed on Apr. 15, 2014, now Pat. No. Des. 764,109, and a continuation-in-part of application No. 29/488,096, filed on Apr. 15, 2014, now Pat. No. Des. 764,711, and a continuation-in-part of application No. 29/488,093, filed on Apr. 15, 2014, now Pat. No. Des. 770,685, and a continuation-in-part of application No. 29/488,099, filed on Apr. 15, 2014, now Pat. No. Des. 777,983, and a continuation-in-part of application No. 29/488,098, filed on Apr. 15, 2014, now Pat. No. Des. 764,712, and a continuation-in-part of application No. 29/488,100, filed on Apr. 15, 2014, now Pat. No. Des. 764,713, and a continuation-in-part of application No. 29/488,101, filed on Apr. 15, 2014, now Pat. No. Des. 764,714, and a continuation-in-part of application No. 29/488,097, filed on Apr. 15, 2014, now Pat. No. Des. 766,512, and a continuation-in-part of application No. 29/488,095, filed on Apr. 15, 2014, now Pat. No. Des. 764,710, and a continuation-in-part of application No. 29/488,094, filed on Apr. 15, 2014, now Pat. No. Des. 764,108, and a continuation-in-part of application No. 29/486,497, filed on Mar. 31, 2014, now Pat. No. Des. 804,099, and a continuation-in-part of application No. 29/479,120, filed on Jan. 13, 2014, now Pat. No. Des. 764,106, and a continuation-in-part of application No. 29/479,117, filed on Jan. 13, 2014, now Pat. No. Des. 764,105, said application No. 29/570,374 is a continuation of application No. 29/479,116, filed on Jan. 13, 2014, now Pat. No. Des. 762,329, said application No. 29/573,625 is a continuation-in-part of application No. 29/479,122, filed on Jan. 13, 2014, now Pat. No. Des. 764,107, and a continuation-in-part of application No. 29/479,121, filed on Jan. 13, 2014, now Pat. No. Des. 763,512.

CLAIM

The ornamental design for cosmetic product container, as shown and described.

DESCRIPTION

FIG. 1 is a front elevational view of a cosmetic product container showing my design;

FIG. 2 is a rear elevational view thereof;

FIG. 3 is a top plan view thereof; and,

FIG. 4 is a bottom plan view thereof.

The broken lines are included for the purpose of illustrating portions of the cosmetic product container that form no part of the claimed design.

1 Claim, 2 Drawing Sheets

*FIG. 1**FIG. 2**FIG. 3*

FIG. 4
